UNITED STATES PATENT OFFICE.

ANKER PETERSEN, OF WINTHROP, MASSACHUSETTS.

STRAND-GUIDE FOR BRAIDING-MACHINES.

1,254,066.

Specification of Letters Patent. Patented Jan. 22, 1918.

Application filed April 11, 1916. Serial No. 90,503.

To all whom it may concern:

Be it known that I, ANKER PETERSEN, a citizen of the United States, and resident of Winthrop, in the county of Suffolk and State of Massachusetts, have invented new and useful Improvements in Strand-Guides for Braiding-Machines, of which the following is a specification.

This invention relates to rotary braiding machines, and particularly to the strand guides or strand-carrying levers in machines of the general type described in Letters Patent of the United States No. 1,105,452, issued to me July 28, 1914. The strand guides or levers set forth in my said former patent are stiff arms pivoted to standards carried on a revolving frame and oscillated up and down by a stationary cam path to guide the strands over and under the several thread carriers, which are revolved by another frame in the opposite direction.

For a fuller description of a type of machine to which the present invention is applicable, reference may be had to the aforesaid patent which will illustrate the environment in which this invention is intended to operate. The present invention relates exclusively to the strand-carrying levers, and only such fragmentary parts of the machine as a whole will be herein described as are necessary to make clear the position of the levers in the machine.

In the accompanying drawings which illustrate one embodiment of the invention,

Figure 1 is an elevation of my improved strand guide or lever;

Fig. 2 is a plan view of the same, showing its relation to the revolving frame and the operating cam;

Fig. 3 is a section on line 3—3 of Fig. 2; and

Fig. 4 is a section on line 4—4 of Fig. 1.

A represents the periphery of the rotary frame which carries the several strand guides or levers, and B represents the stationary cam ring having a cam path b for oscillating the strand guides up and down.

The strand guide or lever as herein shown comprises two main sections, namely, a flat tempered steel spring 1, the broader surface of which lies in a horizontal plane, and the guide arm 2 made of a thin strip of metal curved to conform to the periphery of the

rotary frame, the broader surface of which extends in a vertical plane.

The arm 2 is bent or twisted to a quarter turn, and the turned part 3 at the rear end is riveted to the forward end of the spring 1 by rivets 4, 4. The rear end of the spring 1 is secured between two leaf springs 5, 5, and the whole fastened by a bolt or screw 6 to a support, consisting of a boss or shelf a on the rotary frame A. The leaf springs 5, 5, prevent the repeated bending strain to which the spring 1 is subjected from breaking or weakening the spring 1 on a line close to the supporting shelf or boss a.

The forward or free end of the arm 2 is preferably tapered as shown in Fig. 1, and a notch 7 is formed in the extremity of the arm to serve as a guide for the thread or strand T. On the outer face of the arm 2 is mounted a swivel or rocking cam follower 75 in the form of a wooden block 8, which travels in the cam path b of the stationary cam ring B as the strand guides are revolved about the machine with the revolving frame A. The cam follower 8 is pivoted to rock 80 on a pin 9, which is made with an enlarged shoulder or hub 10 between the cam follower 8 and the arm 2, and projects through the arm 2 to which it is fastened by the head 11.

An eye or ring 12 is fastened to the boss 85 a near the rear end of the strand guide. The strand or thread T passes from the cop or other source of supply (not shown) through the eye 12, thence along the upper side of the spring 1 and around the front 90 side of the arm 2 and over the hub 10 between the arm 2 and the cam follower 8, through the notch 7 at the extremity of the strand guide, and thence to the center of the machine where the fabric is formed.

As the revolving frame A carries the strand guides or levers about the machine, the strand guides are caused to vibrate up and down by the cam path b and cam follower 8, the spring 1 of the levers bending 100 to permit such vibration.

It will be understood that the cam path b follows an up and down wave-like curve, and the relative speed of the machine and the flexibility of the spring 1 are such that 105 in operation the rise and fall of the strand-carrying lever is substantially coincident with the normal vibration which the lever would make on spring 1 were such vibration started by deflecting the spring 1 and then 110

releasing the lever. Thus very little power is required to operate the strand guiding lever and very little wear either on the cam surface or the cam follower results. The device may be very lightly built, and instead of working on a pivot which wears rapidly on account of the rapid motion of the strand guide, the vibration is permitted by the mere bending of the tempered steel spring 1. As the steel spring 1 is made in a separate piece from the rest of the lever it can be readily replaced by inserting a new one in case it should break or become worn. The part 2 having its broader dimension in a vertical plane, is sufficiently stiff in a vertical direction, so that the tension of the thread will not deflect it in a vertical direction, while the part 2 is sufficiently resilient in a radial direction, relative to the machine, to yield a little under the tension of thread T, thereby preventing any variation in tension from breaking the thread.

I claim:

1. In combination with the relatively movable frame and cam of a braiding machine, a strand-carrying lever rigidly secured at one end to the frame, and a cam follower on the lever, said lever including a spring between the cam follower and the rigid securing to the frame, whereby the oscillation of the lever by the cam will be permitted by the bending of the spring.
2. In combination with the relatively movable frame and cam of a braiding machine, a support on said frame, and a strand-carrying lever, comprising a flat spring section at one end secured to said support, a relatively unyielding section at the free end, and a cam-follower on the latter section, the oscillation of the lever by the cam being permitted by bending the spring.
3. In combination with the relatively movable frame and cam of a braiding machine, a support on said frame, and a strand-carrying lever comprising a flat spring section at one end secured to said support, a relatively unyielding section at the free end, a cam-follower on the latter

section, the oscillation of the lever by the cam being permitted by bending the spring, and reinforcing leaf-springs overlying the end of the spring section which is secured to the support.

4. In combination with the relatively movable frame and cam of a braiding machine, a support on said frame, and a strand-carrying lever comprising a flat spring section at one end, having its broader dimension disposed in a horizontal plane and secured to said support, and a flat metal strip section at the free end, having its broader dimension disposed in a vertical plane.

5. In combination with the relatively movable frame and cam of a braiding machine, a support on said frame, and a strand-carrying lever mounted on said support provided with a cam-follower and having a spring interposed between the free end of the lever and the support, adapted to permit the lever to be oscillated by the cam by bending the spring, said cam-follower consisting of a block pivoted to rock upon said lever.

6. In combination with the relatively movable frame and cam of a braiding machine, a support on said frame, and a strand-carrying lever comprising a flat spring section at one end, having its broader dimension disposed in a horizontal plane and secured to said support, and a flat metal strip section at the free end, having its broader dimension disposed in a vertical plane, said lever being curved to conform to the curvature of said frame.

7. A strand-carrying lever comprising a flat steel spring rear section, and a forward section of strip metal, the rear end of which is twisted to a quarter turn and secured to the forward end of the spring section, and the forward end of which is provided with a thread guiding notch.

Signed by me at Boston, Massachusetts, this 1st day of April, 1916.

ANKER PETERSEN.
